UNITED STATES PATENT OFFICE.

HERBERT J. PFEIFFER, OF NEW BRITAIN, CONNECTICUT, ASSIGNOR, BY MESNE ASSIGNMENTS, TO THE BURNS & BASSICK COMPANY, OF BRIDGEPORT, CONNECTICUT, A CORPORATION OF CONNECTICUT.

DRAWER-SLIDE AND THE LIKE.

1,161,330.

Specification of Letters Patent. Patented Nov. 23, 1915.

Application filed July 11, 1911. Serial No. 637,879.

To all whom it may concern:

Be it known that I, HERBERT J. PFEIFFER, a citizen of the United States, and a resident of New Britain, in the county of Hartford and State of Connecticut, have invented 5 certain new and useful Improvements in Drawer-Slides and the like, of which the following is a specification.

This invention relates to any article of 10 furniture employing sliding drawer compartments or other receptacles and its object is to provide an improved bearing on which such receptacles can be easily and conveniently moved.

15 In the drawings: Figure 1 is a side elevation of the device made in accordance with my invention. Fig. 2 is a top view thereof.

Referring to the drawings my device comprises a body part *a* with end projections 20 *b*—*b* fitting into apertures in the frame of the desk, bureau or other structure in order to properly position and hold the device in place.

The body *a* is slotted throughout the 25 greater part of its length as at *c* to receive a shaft *d* to the ends of which on either side of the body are secured the rollers *e*. The slotted body forms a track on which the shaft rolls and the rollers are free to

rotate on the shaft. The fin *f* on the body 30 rides in a groove *g* in the drawer or other movable part and acts as a guide for the drawer. It will be noted that the drawer is structurally quite separate from the slide, and the rollers which support the drawer 35 are freely movable on their shaft, and the shaft in the slide. Preferably the body is formed from sheet metal and the rollers are stamped up into cup shape.

The device as herein above illustrated and 40 described is extremely simple, inexpensive to manufacture, easily renewable in any of its parts and extremely efficient in its operation.

45 I claim as my invention:—

In a device of the character described, a body member provided with means for securing it in position, and having a longitudinal slot, a shaft extending through said slot and having a rolling support on one edge thereof, rollers rotatably mounted on the ends of said shaft at each side of the body member, and a fin at the top of the body member upstanding above said rollers.

50 HERBERT J. PFEIFFER.
